DESIGN FOR A BRUSH FRAME

Conrad Jobst, Toledo, Ohio, assignor to The Owens Staple-Tied Brush Company, Toledo, Ohio, a corporation of Ohio

Application October 27, 1941, Serial No. 103,909

Term of patent 14 years

To all whom it may concern:

Be it known that I, Conrad Jobst, a citizen of the United States of America, residing at Toledo, in the county of Lucas, in the State of Ohio, have invented a new, original, and ornamental Design for a Brush Frame, of which the following is a specification, reference being had therein to the accompanying drawing, forming a part thereof, wherein:

Figure 1 is a side elevational view of a brush frame embodying my new design;

Figure 2 is a top plan view thereof;
Figure 3 is a cross section on the line 3—3 of Figure 2; and

Figure 4 is a cross section on the line 4—4 of Figure 2.

I claim:

The ornamental design for a brush frame, substantially as shown.

CONRAD JOBST.
